UNITED STATES PATENT OFFICE.

GEORGE A. WIELAND, OF DULUTH, MINNESOTA.

DESIGN FOR A PENCIL-TIP.

SPECIFICATION forming part of Design No. 24,143, dated March 26, 1895.

Application filed January 15, 1895. Serial No. 535,037. Term of patent 14 years.

To all whom it may concern:

Be it known that I, GEORGE A. WIELAND, a citizen of the United States, residing at Duluth, in the county of St. Louis and State of Minnesota, have invented and produced a new and original Design for a Pencil-Tip, of which the following is a specification.

The accompanying drawing represents my design for a pencil tip in perspective.

10 The tip has a hollow cylindrical body, *a*, and a series of radial imperforate points, *b*, which are arranged circumferentially, in the same plane, equidistant from the ends of said body,

thus forming a figure which in its main character is star-like.

15 What I claim is—

The design for a pencil tip, consisting of a hollow cylindrical body and a series of radial points which are imperforate and arranged in the same plane, intermediately of the ends 20 of said body, as shown.

GEORGE A. WIELAND.
